THREE-DIMENSIONAL GAME BOARD

T. Walton Westlake, P.O. Box 256, Philipsburg,
St. Martin, Netherlands Antilles

Filed May 27, 1970, Ser. No. 23,168

Term of patent 14 years

Int. Cl. D21—01

U.S. Cl. D34—5

The figure is a perspective view from the lower right of my new design of a game board;

The stepped blocks are affixed to the board.

I claim:

The ornamental design for a three-dimensional game board, as shown and described.
